UNITED STATES PATENT OFFICE.

CHARLES S. JOHNSON, FRANK W. BARBER, AND MICHAEL A. BARBER, OF NORWICH, CONNECTICUT; SAID MICHAEL A. BARBER ASSIGNOR TO LYDIA A. BUCKINGHAM, OF SAME PLACE.

MALT-STIRRING MACHINE.

SPECIFICATION forming part of Letters Patent No. 417,488, dated December 17, 1889.

Application filed October 15, 1888. Serial No. 288,155. (No model.)

To all whom it may concern:

Be it known that we, CHARLES S. JOHNSON, FRANK W. BARBER, and MICHAEL A. BARBER, all citizens of the United States, and residents of Norwich, in the county of New London and State of Connecticut, have invented certain new and useful Improvements in Malt-Stirring Machines, which improvements are fully set forth and described in the following specification, reference being had to the accompanying three sheets of drawings.

Our invention is in that class of malting-machines in which a rotary agitator is employed to move the grain while germinating, to prevent said grain from becoming unduly heated; also, to stir the same during the process of drying. During these stages of germination and drying it is absolutely necessary that means be provided to separate the individual particles and allow the air to occasionally circulate through the mass of grain; otherwise said grain becomes overheated, soured, and rendered unfit for use.

In the attempts heretofore made to produce malt by means of machines embodying so-called "agitators," "stirrers," or "brushes" the chief difficulty has been met during the stage of germination of the barley, at which time the fine rootlets that put forth from said grain become so firmly intertwined and interlocked with each other that the whole mass becomes as a mat or woven fabric that cannot easily be torn apart. When stirrers in the form of plows or shovels are utilized, masses of the matted grain corresponding to the capacity of such plows or shovels are lifted and deposited again without tearing apart and separating the particles of grain.

The object of our present invention is to improve the form and action of malting-machine agitators and also the mechanism by which such agitators are controlled and operated.

For the purpose of more clearly explaining said improvements we have provided the annexed drawings, in which—

Figure 1 is a longitudinal vertical sectional view of a malting-machine embodying our

improvements; and Fig. 2 is an elevation of 50 a complete machine, as viewed from the left-hand end of Fig. 1, and illustrates particularly the mechanism for actuating the several operative parts of such a machine. Fig. 3 is a plan view of the driving mechanism located beneath the floor of the malting-chamber. Fig. 4 is an enlarged detached view of the hanger that supports the agitator and its connected parts at the end where the devices for rotating said agitator are located. Fig. 5 is 55 an elevation of the hanger proper used at one end of said agitator, and Fig. 6 is a similar view of the companion hanger. Fig. 7 is a top or plan view of the hanger illustrated in Fig. 5.

In these several views like letters refer to 60 like parts.

The general form of malting-machine which we prefer to use is that of a rectangular chamber, which for convenience and economy of 70 space may be built between two floors *a* and *b*, the ends and sides being also suitably enclosed. The chamber or box thus provided is then subdivided into an upper and lower compartment by a perforated floor *c*, through 75 which in practice a current of air of desired temperature may be drawn or forced through the grain resting on said perforated floor, such air being introduced to the lower compartment through one or more pipes *d*, connecting with a furnace or refrigerating-room.

The agitator which we use to stir and separate the grain consists of a shaft *e*, extending from side to side of the upper compartment and carrying a series of straight radial wings 85 *e'*. Shaft *e* is supported at each end in bearings *e²* *e³*, that form parts of strong cast-metal hangers *A A'*. These hangers, near their upper end, have laterally-projecting arms *f*, and secured to each of said arms at a point about 90 midway of their length by a bolt or screw *g* is a metallic frame *B*, that projects beyond the end of arm *f* and has pivoted in its free end a roll *h*. In the free end of arms *f* is a vertically-movable screw *i*, whose lower end 95 engages a laterally-projecting lug *k* on frame *B*, as shown in Fig. 4 of the drawings. This arrangement of the rolls *h* (which in practice

support the agitator and its actuating devices) provides a limited vertical adjustment of said agitator. It is sometimes desirable to elevate said agitator, or to lower it into closer engagement with the perforated floor, or to adjust one end relative to the other end, and such results may be quickly and easily accomplished by adjusting the screws *i*.

The lower portion of hanger *A* is formed as 10 a vertical plate *m* with beveled ends that turn the grain inward in front of the agitator, and thus prevents said grain from reaching and clogging the driving mechanism.

On the end of shaft *e* is a gear *C*, that meshes 15 with a corresponding gear *D*, journaled in the upper portion of hanger *A*.

Adjacent to and moving with gear *C* is a score-pulley *E*, around which passes a bight of a cable *G*. This cable is suitably guided 20 to prevent it from running off from said pulley by rolls or sheaves *n n*, one on each side of said score-pulley, said guide-rolls being journaled on a supporting-frame secured to the hanger by bolts *o*. Cable *G* passes out 25 ward through the end walls of the malting-chamber and around score-pulleys *H H'*, the former of which is secured to and rotates with a shaft *J*, that is driven by a belt *p*, connecting said shaft *J* and a counter-shaft *K*, located 30 beneath the floor *b*. When shaft *K* is set in motion, the score-pulleys *H H'* and cable *G* begin to move, causing rotary motion to be imparted to the pulley *E* and its attached gear *D*. This rotates the agitating device, 35 and the wings *e'* act to pick up a given quantity of grain and deposit it in the rear of said agitator. The advance movement of said agitator is accomplished through cables *N N*, located at each side of the malting-chamber 40 and secured to the hangers above described at points approximately level with the agitator-shaft. These cables *N N* are coiled around drums *P P* at the opposite ends of the machine, the drums at one end being hung in 45 adjustable journal-bearings *s*, (see Fig. 1,) so that the slack of cables *N N* may be readily taken up. The shaft *R*, that carries the drums at the opposite end, also bears a bevel-gear *S*, that meshes with a corresponding gear *S'* on 50 a vertical shaft *T*, whose lower end is connected to shaft *K* by a pair of bevel-gears *t t'*. It will now be understood that when shaft *K* begins to rotate the agitator simultaneously begins to rotate and advance through the mass 55 of grain. The rotation of said agitator relative to its advance movement should be so regulated that the wings *e'* may pick up the grain freely and rapidly enough so that said grain may not accumulate and pile up in front of 60 the agitator.

Adjacent to shaft *K* is a parallel counter-shaft *V*, carrying fast and loose pulleys *v' v'*, that are driven by straight and crossed belts *w w'*, so that said shaft *V* may be caused to 65 rotate in opposite directions when desired. A belt *x* connects said pulleys *v' v'* with a wide pulley *y* on shaft *K*. By transferring

belt *x* from one to the other of said pulleys *v' v'* the direction of rotation of shaft *K* and of its connected mechanism is controlled. 70 To accomplish this reversal and so change the direction of travel of the agitator we have provided an automatic belt-shifting device, arranged as follows: At each end of the malting-chamber, in the path of the carriage that supports the agitator, is pivoted a lever-arm *z*, whose pivotal shaft has on its outer end a lever *z'*. (Indicated by dotted lines in Fig. 1.) The ends of these levers are connected by cables or chains *z²*, so that 80 a rocking motion of one arm *z* imparts like motion to the companion arm at the other end of the machine. The lever *z'* nearest the counter-shaft *V* bears also a lever or cross-head *z³*, whose ends have cords *z⁴ z⁵* 85 leading downward therefrom. The other ends of said cords are attached, respectively, to the ends of a shipper-lever *W*, that controls the lateral movement of belt *x*. When the agitator has nearly reached the end of 90 the malting-chamber, its carriage engages and moves the arm *z*, and through the described medium of levers, cords, and shipper-lever belt *x* is transferred to the adjacent pulley *v'* or *v'*, as the case may be, and thus 95 the movement of said agitator is reversed.

It should be understood that the rolls *h h* travel on a track or ledge *O*, secured to the side walls of the malting-chamber, and that the agitating device is, in fact, suspended on 100 these rolls, so that the perimeter of said agitator is not in actual contact with the perforated floor, but the wings *e'* pass close to said floor as they rotate.

The several mechanisms utilized to move 105 the cables that drive the agitator are simple and positive in their action and not expensive to produce.

Having described our invention, we claim as new and desire to secure by Letters Patent— 110

1. In combination, in a malting-chamber having a perforate floor, a rotary agitator, cable mechanism, substantially as herein set forth, for moving said agitator, and hangers having journal-bearings in which the shaft 115 of said agitator is hung, said hangers being formed with laterally-projecting vertically-adjustable arms *B*, bearing rolls *h*, as specified.

2. In combination with a malting-chamber, 120 a rotary agitator, and cable mechanism, substantially as set forth, for actuating the same, hangers having journal-bearings in which the shaft of said agitator is hung, one of said hangers being formed with a vertical plate 125 *m*, having beveled ends to throw the grain in front of the advancing agitator, substantially as and for the object specified.

3. In combination with a malting-chamber, 130 a rotary agitator, and cable mechanism, as set forth, for actuating the same, hangers having journal-bearings in which the shaft of said agitator is hung, said hangers being provided with and supported by traction-

rolls pivoted in vertically-adjustable arms B, attached to said hangers, as set forth, one of said hangers being also provided with a vertical plate *m* with beveled ends, all substantially as and for the objects specified.

4. In a malting-chamber, an agitator consisting of a shaft bearing straight radial blades *e'* and a gear C, in combination with hangers in which said shaft is journaled, a gear D, also journaled in said hanger and meshing with said gear C, a score-pulley adjacent to and moving with said gear D, a

cable coiled about said score-pulley, guide-rolls *n n*, supported by a frame secured to said hanger, as set forth, and mechanism, substantially as herein described, for moving said cable, for the purpose stated. 15
